UNITED STATES PATENT OFFICE

153,595

DESIGN FOR A MARINE RADIO TELEPHONE

Gordon W. Florian, Trumbull, Conn., assignor to
Hudson American Corporation, New York,
N. Y.

Application July 31, 1947, Serial No. 140,644

Term of patent 7 years

(Cl. D26—5)

To all whom it may concern:

Be it known that I, Gordon W. Florian, a citizen of the United States, residing at Trumbull, in Fairfield County and the State of Connecticut, have invented a new, original, and ornamental Design for a Marine Radio Telephone, of which the following is a specification, reference being had to the accompanying drawing, forming part thereof.

My present application is a continuation in part of my application Ser. No. D-124,843, filed December 19, 1945, now abandoned.

Fig. 1 is a front perspective view of a marine radio telephone showing my new design, the view being taken as from the left; and

Fig. 2 is a front perspective view of the same.

I claim:

The ornamental design for a marine radio telephone, substantially as shown.

GORDON W. FLORIAN.
